UNITED STATES PATENT OFFICE

DELMER I. PLETSCHER, OF LONG BEACH, CALIFORNIA

HYPODERMIC SYRINGE

Application filed May 11, 1938. Serial No. 276,962.

The present invention relates to hypodermic syringes and has for its principal object to provide a serum or medicament cartridge arranged for removably mounting in operative association with the ejecting means of the needle in a manner for discharging the serum through the needle end thereof.

A further important object of the invention is to provide a cartridge of this character having a needle forming a discharge nozzle at one end thereof and providing a combined stopper and plunger at the opposite end thereof in operative association with the ejecting means of the needle whereby to force the serum through said nozzle.

A still further important object of the invention is to provide a plastic coating for both the needle and plunger ends of the cartridge forming a sanitary and liquid tight seal therefor and to protect the same until ready for use.

A still further important object of the invention is to provide a used connection for the needle with the discharge end of said cartridge.

An additional object is to provide an article of this character of a simple and practical construction, which is efficient and reliable in performance, sanitary, which enables the serum in the cartridge to be stored for any definite period without danger of deterioration, which permits of a reduction in the number of parts entering into the construction of a hypodermic syringe of this character and thereby promote economy in the manufacture thereof, and which is otherwise well adapted for the purposes for which the same is intended.

Other objects and advantages reside in the special construction, combination and arrangement of the various elements forming the invention as more fully hereinafter described and claimed, reference being had to the accompanying drawings forming parts hereof, wherein like numerals refer to like parts throughout, and in which:

In the drawings:

Figure 1 is a perspective view of the car-

tridge shown provided at each end with the fastening cover,

Figure 2 is a similar view showing such cover removed and with the cartridge ready for use,

Figure 3 is a longitudinal sectional view through the mounting for the cartridge and with the cartridge shown in position therein with its inner end broken away and shown in section,

Figure 4 is a transverse sectional view taken along a line 4-4 of Figure 3,

Figure 5 is a longitudinal sectional view of a simplified serum ejecting means for the cartridge,

Figure 6 is a similar view showing the same after the same has been discharged therefrom and

Figure 7 is an enlarged fragmentary longitudinal sectional view through the needle end of the cartridge and illustrating the manner in which the needle is used therein.

Referring now to the drawings in detail, the invention contemplates the provision of a conventional type of holder for a hypodermic needle, and including a cylindrical barrel 5 open at each end and having one end provided with a slightly inturned flange 6 and with its opposite end externally threaded for receiving a cap 7.

Within the barrel 5 is seated a cylindrical sleeve 8 constituting an adapter and preferably constructed of semi-hard rubber or the like, one end of the sleeve being tapered as shown at 9 and extending outwardly of the flanged end 6 of the barrel and with its outer end of a substantially blunt formation and provided with an opening therein.

The opposite end of the sleeve is closed by the cap 7 and extending longitudinally in the cap is the plunger rod 10 having an operating knob 11 formed at its opposite outer end and with a disk head 12 formed at its inner end within the sleeve 8.

A cap is also provided with a pair of laterally extending fingers 13 extending at opposite sides thereof. The sleeve 8 is adapted to receive a cylindrical cartridge 14, preferably constructed of transparent material, said cartridge being of a tapered formation at one

end, as shown at 15 and adapted to snugly fit within the tapered end 9 of the sleeve with the tapered end of the cartridge protruding outwardly through the openings in said sleeve.

5 The tapered end of the cartridge 17 is also formed with an opening through which the front end of a tubular hypodermic needle 16 is inserted, the outer end of such needle being 10 of the conventional construction and pointed as shown at 17, the portion of the needle adjacent such pointed end is flattened and provided with a discharge opening 18 as well known in the art.

15 This needle 16 is usually of a metallic construction and is fixedly secured in the tapered end of the cartridge by heating such end of the cartridge and fusing the material of the cartridge about the inner end of the needle.

20 This method of fusibly connecting the needle with the cartridge is illustrated in Figure 7 of the drawing and for this purpose the outer surface of the upper end of the needle is cast roughly as indicated at 19 so as to enable the molten material of the cartridge 25 to more readily adhere to the end of the needle. The needle is also formed with a collar or flange 16' adjacent its secured end for abutting the end of the cartridge and 30 prevent inward movement of the needle.

The cartridge 14 is adapted to contain a quantity of serum or medicament 20 which is retained therein by a stopper 21 having its edges fitted snugly against the inner wall of 35 the cartridge and disposed at the end thereof opposite from the tapered end 15. The stopper 21 may be constructed of any suitable material well known in the art and if desired may be provided with an annular packing 40 ring 22 engageable with the walls of the cartridge to form an absolute air tight and liquid tight seal for the serum within the same.

The stopper 21 is adapted for sliding movement in the cartridge and accordingly upon 45 the assembly of the parts as is illustrated in Figure 3 of the drawings the head 12 of the plunger rod 10 may be placed against the stopper 21 and upon the operation of said rod inwardly through the cap, the stopper 21 may 50 be forced longitudinally of the cartridge for causing ejection of the serum out through the needle 16. The end of the stopper is tapered to correspond with the tapered discharge end of the cartridge whereto force all of the serum 55 therefrom.

The barrel 5 and the sleeve 8 may be formed with aligned longitudinally extended slotted openings 23 and 24 respectively, by means of which the quantity of serum discharged from 60 the transparent cartridge 14 may be observed.

The face of the head 12 disposed in engagement with the stopper 21 may be formed with a lug 25 suitable for penetrating the material of the stopper to prevent transverse movement between the head and stopper during 65

the operation of the rod 10. At the time of filling the cartridge 14 and fitting the stopper 21 in the filling end thereof, both the filling and discharge end of the cartridge may be covered with a quantity of plastic material 70 indicated at 26 and 27 respectively whereby to close both ends of the cartridge against contact with the air or any object prior to the time when the same is mounted in the holder 30 for use.

75 This plastic material may be of a character well known in the art, such as wax or the like. The plastic material is adapted to entirely cover both ends of the cartridge and extends throughout the entire length of the needle 16 as clearly illustrated in Figure 1 of the drawings. When the cartridge is desired for use the plastic material is heated so as to cause a melting of the same and removal from the cartridge before placing the same in the 80 holder.

If desired the cartridge may be in use independent of the holder represented in Figure 3 of the drawings and in lieu of the holder the filling end of the cartridge may be provided 90 with a snugly fitting cap 28 having an insert 29 of packing material, such as cork, rubber or the like, the outer end of said insert being of a reduced diameter enabling the same to fit within the end of the cartridge as clearly 95 illustrated in Figure 5 of the drawing.

Both the cap 28 and the insert 29 are provided with a central opening through which a plunger rod 30 extends having an operating knob 31 on its outer end and arranged 100 with its inner end engaging the stopper or plunger 21 of the cartridge, the operation of said plunger rod serving to eject the serum from the cartridge in a manner as heretofore explained.

105 In this form of the invention, both ends of the cartridge 14 may be protected by a plastic coating similar to that heretofore described. It will be apparent from the foregoing that as soon as the serum from the cartridge has 110 been ejected that the same may be removed from the holder and a fresh cartridge substituted therefor. With respect to the form of the invention illustrated in Figures 5 and 6 of the drawings, the cap for the filling end of the cartridge and the plunger rod 30 may be installed in operative position with respect to the cartridge at the time of manufacture thereof and the plunger rod 30 sealed in position until ready for use by the plastic coating 115 28.

120 In this form of the invention after the cartridge has been used the plunger rod 30 may be destroyed or distorted together with the used cartridge.

125 It is obvious that my invention is susceptible to various changes and modifications in construction without departing from the spirit of the invention or the scope of the appended claims, and I accordingly claim all 130

such forms of the device to which I am entitled.

Having thus described my invention, what I claim as new is:

- 8 1. In combination with a syringe having a plunger rod and a barrel formed with an inwardly tapered outer end, a sleeve-like adapter in the barrel having a tapered outer end which conformably engages said tapered end of the barrel and projects therebeyond, and a cartridge within and engaged with the inner circumference of the adapter and having a tapered end provided with a needle, said cartridge having a piston at its inner end 10 to engage with the plunger rod of the syringe.
2. In combination with a syringe having a plunger rod and a barrel provided with an abutment at its outer end, an adapter within the barrel having a tapered outer end which 20 engages with said abutment to be held thereby against movement out of the front of the barrel, and a cartridge in the adapter having a tapered end provided with a needle and engaged with the tapered end of the adapter 25 and having a piston at its inner end engageable with the plunger rod of the syringe.
3. In combination with a syringe having a plunger rod and a barrel formed with an abutment at its front end, an adapter within 30 the barrel having its front end formed to engage with said abutment so as to be held thereby against movement out of the barrel, a cartridge in the adapter having a needle fixed in its front end and having its said 35 front end engaged with the front end of the adapter so as to be firmly held thereby and a piston in the cartridge operable by the plunger rod of the syringe.

In testimony whereof I affix my signature.

40 DELMER I. PLETCHER.
